UNITED STATES PATENT OFFICE.

PETER C. BURNS, OF CHICAGO, ILLINOIS.

TELEPHONE-RECEIVER.

SPECIFICATION forming part of Letters Patent No. 605,594, dated June 14, 1898.

Application filed November 20, 1897. Serial No. 659,248. (No model.)

To all whom it may concern:

Be it known that I, PETER C. BURNS, a citizen of the United States, residing at Chicago, in the county of Cook and State of Illinois, 5 have invented a certain new and useful Improvement in Telephone-receivers, of which the following is a specification.

My invention has for its object the production of means, simple and effective in action, 10 by which the distance or space between the end of the permanent magnet or the pole of such magnet and the diaphragm may be adjusted accurately and readily and when adjusted securely held in the adjusted position. 15 It also has for its object the ready removal of the casing of the receiver to give access to the permanent magnet, wires, and other electrical agencies inclosed therein.

Reference may now be had to the accompanying drawings, in which—

Figure 1 is a central longitudinal section completely through the telephone-receiver. Fig. 2 is a like view showing the parts detached and ready to be assembled. Fig. 3 is a section on the correspondingly-numbered line 25 in Fig. 1 seen in the direction of the arrow, the casing being removed.

In carrying out my invention I provide a cup-shaped member which is screw-threaded 30 to receive the cap of the receiver, which holds the diaphragm. When the cap holding the diaphragm is screwed upon the cup-shaped member, they together form a chamber within 35 which the end of the permanent magnet of the receiver or the pole of the receiver is positioned. The cup-shaped member, with the diaphragm-cap secured thereto, is held upon a collar fixed on the end portion of the permanent magnet and connected by screw- 40 threads therewith. The collar holds a disk having at intervals stop-screws which, passing through the disk, will impinge and bear against the rim of the cup-shaped member. The cup-shaped member, with the cap thereon 45 and the diaphragm contained therein, is adapted for movement along the permanent magnet by virtue of the screw-threaded connection between the collar and the cup-shaped member, thus drawing the diaphragm toward 50 or away from the end or pole of the permanent magnet and adjusting the same in proper

relative position thereto. When the proper adjusted position is obtained, the stop-screws are firmly brought to bear against the rim of the cup-shaped member, thus holding the 55 same securely in this adjusting position.

Referring now to the accompanying drawings, the permanent magnet of the receiver is designated at A of the usual form and construction and having a pole-piece A² at the 60 end thereof. The diaphragm-cap is designated at B, holding thereon the diaphragm B². The cup-shaped member is designated at D and may be termed the "adjusting-ring." A collar E, screw-threaded at a and having a 65 shank E², is secured by said shank to the permanent magnet A with a screw E³. The pole-piece A² is screwed into the collar E. The usual helix or coil H is positioned upon the pole-piece A². The adjusting-ring D has an 70 annular flange extension b, which is provided with internal screw-threads adapted to mesh with the threads a of the collar E. The cap B is screwed upon the adjusting-ring D and the diaphragm B² is held between these two 75 members.

From the foregoing it is evident that a chamber J is provided by means of the cap B and the adjusting-ring D, within which is positioned the pole-piece A², the coil H, and the 80 diaphragm B².

The collar E has an annular disk secured or formed therewith, (designated at K,) through which the stop-screws K² are extended, the ends of which screws impinge and bear 85 against the rim K³ of the adjusting-ring D.

In order to adjust the diaphragm B² in proper position and move the same toward and away from the end of the pole-piece A², it is only necessary to revolve the adjusting- 90 ring D upon the collar E by means of the screw connection between them, this revolution, in fact, causing the adjusting-ring D to move back and forth on the collar, and as the diaphragm-cap B is secured to said adjusting- 95 ring D the diaphragm B² is thus caused to move back and forth and toward and away from the end of the pole-piece A² in order to secure the proper adjustment.

It is evident that before the adjusting-ring 100 D can be revolved upon the collar E the insulating-sleeve L, screw-threaded upon the

collar E and acting as a jam-nut against the adjusting-ring, must be unscrewed wholly or partially from said collar.

When the diaphragm is properly positioned 5 relative to the end of the pole-piece A², the stop-screws K² are then screwed down upon the rim K³ of the adjusting-ring D and hold the diaphragm-cap B and the diaphragm B² in this adjusted position and form a gage by 10 which the parts can be readily restored to the same adjustment if for any reason taken apart.

It is often desirable to give access to the permanent magnet or to the internal wiring 15 of the receiver or to the pole-piece and its spool without disturbing the relations of these parts. To this end in the present invention the insulating-sleeve I is so constructed that it can be slipped over the binding-screws l l', 20 which for this purpose are mounted in an independent disk J' of insulating material secured to the yoke of the permanent magnet in any suitable manner—as, for instance, by spacing-thimbles l² and screws l³, passing 25 through said thimbles. The insulating-disk is of such diameter as to fit and close the bore at the adjacent or heel end of the insulating-sleeve when the latter is in position with the other parts, and this bore is continued 30 throughout the length of the sleeve, preferably of the same diameter, but necessarily of no smaller diameter, so that when the sleeve is detached from the collar E it may be slipped endwise over the disk, as indicated in Fig. 2. 35 The adjusting-ring D, since its bore is of the same diameter as the bore of the adjacent end of the insulating-sleeve, both screwing upon the same collar E, can also be slipped over the insulating-disk and binding-screws, 40 while the diaphragm and diaphragm-cap are

removable at the opposite end of the apparatus, leaving the permanent magnet, pole-piece, helix, and receiver-wires 14 undisturbed and open for inspection and repairs.

Having thus described my invention, what 45 I claim as new therein is—

1. In a telephone-receiver, a permanent magnet, a collar mounted thereon, a diaphragm-cap, a diaphragm and a cup-shaped member to which the diaphragm and cap are 50 secured, and a screw connection between the cup-shaped member and the collar whereby the diaphragm may be adjusted in proper position relative to the pole-piece together with a disk on the collar and stop-screws in said 55 disk adapted to bear against the cup-shaped member and lock the parts in adjusted position.

2. In a telephone-receiver, the combination 60 with the permanent magnet and its accessories of the insulating-disk secured to the heel thereof and carrying the binding-screws, the insulating-sleeve bored lengthwise to slip over said disk, the collar upon which said sleeve screws, and the adjusting-ring also screwing 65 upon said collar and adapted to slip over said disk, and the diaphragm and diaphragm-cap.

3. In a telephone-receiver the combination 70 with the permanent magnet and its accessories of the insulating-disk secured to the heel thereof, the sleeve adapted to slip over said disk, the screw-threaded collar, the adjusting-ring, the stop-screws, the diaphragm and the diaphragm-cap.

In testimony whereof I affix my signature 75 in presence of two witnesses.

PETER C. BURNS.
